TO VALLEY IRON WORKS COMPANY, OF APPLETON, WISCONSIN, A CORPORATION
OF WISCONSIN.

DECKLING MECHANISM FOR PAPER-MAKING MACHINES.

Application filed January 3, 1928. Serial No. 244,074.

This invention relates to deckling mechanism for paper making machines, and has for its principal object, to provide improved mechanism for effecting the deckling operation on the wire of a paper making machine, for instance, on the Fourdrinier wire of a Fourdrinier paper making machine, and also to provide deckling mechanism operative between the stock-flow-regulating plate and 10 apron over which the stock flows from the head box to the wire or other stock receiving part, in the case of a so-called "Voith inlet".

Other objects of the invention are to provide an efficient deckling device of simple construction for use between the regulating plate and apron above referred to; to provide such a deckling device which is adjustable cross-wise of the machine between the regulating plate and apron to vary the width of the 15 flow of stock therebetween; to provide such a device which is adjustable to closely fit the vertical dimension or depth of the space between the regulating plate and apron, and also to provide such a device which is automatically self-adjustable to fit the depth of 20 said space.

Further objects of the invention are to provide improved means for mounting the deckle strap guide pulley of a standard type 25 of paper making machine so as to permit movement thereof from its normal position, thereby to facilitate repairing, cleaning or other operations on the wire or other parts to which access is otherwise obstructed by the 30 pulley and its support; to provide improved means for effecting adjustment of the deckle strap for controlling the width of the flow of stock on the wire, and to provide means 35 whereby the deckle strap and the above-mentioned deckling device may be simultaneously adjusted as a single unit.

Other objects and advantages of the invention will be understood by reference to the following specification and accompanying drawings in which we have illustrated so much of a Fourdrinier type of paper making machine as is necessary to enable a person skilled in the art to fully understand the present invention.

50 In the drawings:

Fig. 1 is a side elevation of a portion of a paper making machine showing the head box, apron over which the paper stock flows from the head box to the wire, the regulating plate

over the apron, the end of the wire adjacent 55 the head box, and the deckling strap and its guide pulley.

Fig. 2 is a plan of part of the mechanism shown in Fig. 1.

Fig. 3 is a section on the line 3—3 of Fig. 1, 60 the wire-supporting rolls being omitted to promote clarity.

Fig. 4 is a section on the line 4—4 of Fig. 3.

Fig. 5 is a perspective of the deckling device used between the regulating plate and 65 apron.

Fig. 6 is a section on the line 6—6 of Fig. 3.

Referring now more particularly to Figures 1 and 2 of the drawings, the head box of a paper making machine is indicated at 10, 70 supported by any suitable framework 11 and provided with a discharge opening 12 in its front wall 13. A distributor roll 14 of any desirable form is rotatably mounted in bearings such as shown at 15 on opposite sides of 75 the head box and serves to produce a uniform distribution of the fibers contained in the paper stock as it flows out of the head box through the discharge opening 12.

For controlling the discharge opening 12, 80 a gate 16 is provided which is adjustable vertically to open or close the opening as desired. This gate is suitably mounted in guideways, and means may be provided for facilitating adjustment thereof and also locking the gate in the desired position. Such means forms no part of the present invention and therefore need not be specifically described.

A wire 17 (for instance, a Fourdrinier 90 wire) passes around a breast roll 18 and a couch roll (not shown) and is supported intermediate the rolls by means of a plurality of supporting rolls 19. The breast roll 18 and supporting rolls 19 are, of course, suitably mounted in supporting side frames which are omitted in the present disclosure, since this structure is well known to those skilled in the art. A deckle strap 20 and deckle-strap-guidepulley 21 are arranged over the wire 17 so that the lower reach 20a of the strap will be effective to control the width of the flow of stock on the wire. The guide pulley 21 is rotatably mounted in an improved manner which will hereinafter be fully described. For conveying the paper stock from the head box 10 to the wire 17, the head box 10 is provided with a bottom plate 22 which 100

105

extends outwardly from the box adjacent the lower edge of the discharge opening 12. An apron 23 of rubber or other suitable material is secured to said bottom plate 22 and supported by an extension plate 24 which extends from the forward edge of the bottom plate 22 to a point in very close proximity to the wire 17 so that the apron is well supported between the forward edge of the bottom plate and the point at which the apron actually engages and rests on the wire, as shown at 25. The apron, of course, extends lengthwise over the wire some distance beyond the breast roll so as to deliver the wet paper stock to the wire at the proper point.

For further controlling the depth of the flow of stock from the head box on to the wire, a regulating plate 26 is provided which is preferably pivotally mounted, as shown at 27, adjacent the lower edge of the adjustable gate 16. Suitable means including a clamping plate 28 and clamping mechanism 29 are provided for retaining the regulating plate in its pivotal mounting, and adjusting rods such as shown at 30 are connected to the regulating plate adjacent its forward edge for effecting swinging movement of the plate about its pivot. It will be apparent that by raising or lowering the forward edge portion of the regulating plate, the depth of the flow of stock from the head box on to the wire will be effectively controlled.

The deckling device for controlling the width of the flow of paper stock between the regulating plate 26 and apron 23 is best shown in Figure 5, and consists of a back wall portion 35 and a side wall portion 36. The back wall portion is preferably formed of a channel-shaped member 37 and a plate 38 which is mounted on the back of the channel so as to be slidable thereon in such a way that it serves, when extended, to increase the width of the back wall portion 35. The plate 38 is so mounted by means of a guide 39 rigidly secured to the end of the back wall 40 of the channel member and provided with an undercut edge portion 41 which receives a complementary edge portion 42 of the plate 38. The other end of the plate 38 is slidably mounted by means of a track 43 integral with or secured to the plate 38 and fitting over a track 44 projecting from the adjacent end of the back wall portion 40. The plate 38 is also provided with plunger members 45 and 46 secured thereto by means of lugs 47 and 48, and the said plungers are slidable through apertures 49 and 50, respectively, provided in the top wall 51 of the channel member. The plungers 45 and 46 are recessed, as clearly shown in Figure 6, to receive a coil spring 52 and a spring guide pin 53 which is seated in the lower flange or wall 54 of the channel member. The plungers 45 and 46, which slide through the apertures 49 and 50 respectively, are effective to prevent displacement of the

plate 38 from the channel member, and the above described undercut seat arrangement 41 and 42 and track arrangement 43 and 44 serve to steady the plate 38 relative to the channel member.

The side wall portion of the deckling device includes a member 55 rigidly secured to the end of the channel member 35 by suitable means such as a screw shown at 56, the adjacent end of the channel member being provided with a closure portion 57 which is drilled and tapped to receive the screw 56. The member 55 is preferably further connected to the channel member by means of a diagonal brace 58 which is secured by means of screws, as shown at 59 and 60, to the channel member and side member respectively. The member 55 is preferably wedge-shaped, as clearly shown, to fit between the apron 23 and the regulating plate 26, which is usually disposed at an angle relative to the apron as shown. An extension member 61 is pivoted adjacent its upper corner, as shown at 62, to the adjacent upper corner of the rear wall extension plate 38. The said side extension 61 is further provided with guide lugs 63 and 64, which overhang the member 55 so as to position the extension member 61 closely adjacent the outer face of the member 55. and a spring member 66, secured as shown at 67 to the member 55 and engaging the lug 64, is effective to normally tend to swing the outer end of the side extension 61 upwardly about the pivot 62, thereby to increase the effective width of the wedge-shaped side. The springs 52 which operate in the recessed plunger posts 45 and 46 normally tend to force the back wall extension plate 38 outwardly to increase the effective width of the back wall. Hence it will be seen that the deckling device is automatically adjustable to accommodate itself to closely fit the depth of the space between the adjustable regulating plate 26 and apron 23.

The above described deckling device is mounted between the regulating plate 26 and apron 23 so as to be slidable cross-wise of the length of the paper making machine in such a way that the extensible back wall portion of the device is effective when the device is adjusted inwardly to close the end portion of the discharge opening 12 in the head box and so that the extensible side wall portion of the device is effective to control or guide the adjacent edge of the flow of stock between the regulating plate and apron. It will be apparent that if the gate member 16 is adjusted so as to increase or decrease the height of the discharge opening 12, the deckling device, because of its spring-actuated extensible back-wall portion will be automatically adjusted to compensate for the adjustment of the gate 16. The spring-actuated extensibility of the side wall portion of the deckling device also results in automatic

adjustment of the side wall to accommodate itself to any adjustment of the forward edge portion of the regulating plate 26 which may be accomplished through the adjusting rods 30.

For facilitating adjustment of the deckling device crosswise of the machine, we provide an arm 68 integral with the brace 58, and this arm 68 may be provided with a hand grip 10 for permitting convenient manual adjustment, or an arm may be provided with means for attaching the same to mechanism whereby such adjustment may be effected. In the present instance, we provide the arm 68 with 15 an upstanding lug 69 which is adapted to be connected to mechanism which will herein-after be described for effecting the said adjustment.

Any convenient mechanism may be provided for locking the deckling device in any desired position of adjustment between the regulating plate and apron, and in the present instance, we provide a clamping arm 70 which depends from a bracket 71 secured to the front 20 wall 13 of the head box. A stud 72 secured in the front wall of the head box beneath the bracket 71 extends through an aperture in the clamping arm and rotatably receives a cam member 73 provided with a handle 74 25 whereby the cam member 73 may be rotated. A cam member 75 is fixedly secured to the clamping arm 70 so that rotation of the cam member 73 forces the lower end of the arm 70 into engagement with the edge of the top 30 wall 51 of the channel member, thereby to clamp the deckling device between the portion of the head box which it engages and the clamping arm.

The deckle strap guide pulley 21 is rotatably mounted on the inner end of a shaft 80 and is locked thereon against axial movement by means of collars 81 and 82 which are non-rotatably secured to the shaft. A guide finger 81^a integral with the collar 81 is provided 40 for preventing the deckle strap from leaving the guide pulley adjacent the top of the latter, and a paper stock guide 81^b is supported by means of a hanger 81^c secured to the said collar 81. The guide 81^b serves to guide the 45 edge of the flow of stock across the space between the forward end of the deckling device and the adjacent portion of the deckle strap. The shaft 80 is axially slidably mounted in a bearing 83 forming one part of an arm 84 50 which is pivotally mounted on a vertical axis at its opposite end, as best shown in Figures 1 and 2. For the purpose of so mounting the arm 84, we provide a bracket 85 which is pivoted to the side wall of the head box 55 by means of a bolt 86 and which is locked against pivotal movement about the bolt 86 by means of bolts 87 and 88 which pass through slots 89 and 90, respectively, provided in the bracket member. The bracket 60 member 85 is provided with spaced ears 91

and 92, between which a tongue portion 93 of the arm 84 is disposed and pivoted by means of a pivot bolt 94. The tongue portion 93 of the arm is provided with a slot 95 through which a bolt 96 passes into threaded engagement with the side wall of the head box.

It will be apparent that by loosening the bolts 87, 88 and 96, the arm 84 and bracket 85 may be swung in a vertical plane about the pivot bolt 86, and hence that a certain 75 degree of vertical adjustment is provided for the deckle strap guide pulley 21 and the deckle strap 20. It will also be apparent that by removing the bolt 96, the arm 84 may be swung in a horizontal plane about the pivot 80 bolt 94, thereby permitting removal of the deckle strap guide pulley from its normal position over the wire 17, and thereby affording free access to parts of the machine to which access is otherwise obstructed by the 85 deckle strap guide pulley and its supporting arm.

The outer end of the shaft 80 is axially slidably mounted in a suitable bearing 99 provided as a part of the arm 84. A shaft 90 100 provided with screw threading, as shown at 101, threadedly engages an apertured boss 102 also provided on the arm 84 intermediate the bearings 83 and 99, and the outer end of the shaft 100 is rotatably mounted in the connecting arm 98, but locked against axial movement relative thereto by suitable means such as a collar 103 and a hand wheel 104, both of which are rigidly secured to the shaft 100. 105 It will be readily understood that by turning the hand wheel 104 and shaft 100, the connecting arm 98 will be caused to move towards or from the supporting arm 84. Such movement of the connecting arm 98 relative to the supporting arm is effective to move the shafts 100 105 80 and 97 axially through their respective bearings, such movement of the shaft 80 being effective to correspondingly adjust the deckle strap guide pulley crosswise of the length of the paper making machine. Hence 110 it is a very simple matter to adjust the deckle strap inwardly or outwardly crosswise of the machine to control the width of the flow of stock as it is deposited on the wire.

For adjusting the deckling device between 115 the regulating plate and apron, we provide an arm 105 rigidly secured to the connecting arm 98 by means of bolts such as shown at 106, and to the lower end of which one lug 107 of a Z-shaped bracket 108 is rigidly connected. 120 The other lug 109 of the Z-shaped bracket is connected by means of a bolt 110 to the lug 69 of the arm 68. Movement of the connecting arm 98 will be transmitted through the arm 105 and bracket 108 to the deckling device, and hence rotation of the hand wheel 104 125 is operative to simultaneously adjust the deckle strap and the deckling device.

We are aware that changes may be made in the form, construction and arrangement of 130

the parts without departing from the spirit of the invention, the scope of which should be determined by reference to the following claims, which should be construed as broadly as possible consistent with the state of the art.

We claim as our invention:

1. In combination in a paper making machine, a deckle strap, a pulley for guiding said strap, an arm carrying said pulley, and means for vertically and horizontally adjustably mounting said arm on a relatively stationary portion of the machine, and means carried by said arm for effecting axial adjustment of said pulley inwardly or outwardly of the machine.
  2. In combination in a paper making machine, means for receiving a flow of wet paper stock, a deckle strap for guiding the edge of said flow on said receiving means, a pulley for guiding said strap, an arm carrying said pulley, means for mounting said arm so as to permit movement of said arm and pulley away from their normal operative position relative to the wire, thereby permitting free access to be had to the wire.
  3. In combination in a paper making machine, means for receiving a flow of wet paper stock, a deckle strap for guiding the edge of said flow on said receiving means, a pulley for guiding said strap, an arm carrying said pulley, means for pivotally mounting said arm so as to permit swinging of said arm and pulley away from their normal operative position relative to the wire, thereby permitting free access to be had to the wire.
  4. In combination in a paper making machine, a wire for receiving a flow of wet paper stock, a deckle strap for guiding the edge of said flow of stock on the wire, a pulley for guiding said strap, an arm carrying said pulley, means for pivotally mounting said arm on a vertical axis so as to permit said arm and pulley to be swung horizontally away from their normal operative position relative to the wire, thereby permitting free access to be had to the wire.
  5. In combination in a paper making machine, a deckle strap, a pulley for guiding said strap, means for mounting said pulley so as to permit adjustment thereof inwardly or outwardly of the machine, said means comprising a shaft carrying said pulley, a relatively stationary arm mounted on a part of the machine and provided with means for axially slidably receiving said shaft, a second shaft having screw threaded engagement with said arm, means connecting said pulley shaft and second shaft against axial movement relative to each other, and means for facilitating rotation of said second shaft for effecting axial movement thereof relative to said arm and thereby to effect axial movement of said pulley shaft and pulley.
  6. In combination in a paper making ma-
- chine, a head box having a discharge opening, means for receiving a flow of paper stock from said head box, an apron for conducting said stock from said discharge opening to said receiving means, a regulating plate overlying said apron for controlling the depth of the flow of stock thereover, and a deckling device fitting between said apron and regulating plate and slidably adjustable therebetween for controlling the width of the flow of stock.
7. In combination in a paper making machine, a head box having a discharge opening, means for receiving a flow of paper stock from said head box, an apron for conducting said stock from said discharge opening to said receiving means, a regulating plate overlying said apron for controlling the depth of flow of stock thereover, a deckling device fitting between said apron and regulating plate and slidably adjustable therebetween for controlling the width of the flow of stock, and means for effecting adjustment of said deckling device.
8. In combination in a paper making machine, a head box having a discharge opening, means for receiving a flow of paper stock from said head box, an apron for conducting said stock from said discharge opening to said receiving means, a regulating plate overlying said apron for controlling the depth of flow of stock thereover, a deckling device fitting between said apron and regulating plate and slidably adjustable therebetween for controlling the width of the flow of stock, and means for locking said deckling device in the desired position of adjustment.
9. In combination in a paper making machine, a head box having a discharge opening, an apron extending outwardly from the lower edge of said opening, means adjacent the outer end of said apron for receiving a flow of paper stock from said head box, a regulating plate overlying said apron and vertically adjustable for controlling the depth of the flow of stock over said apron, and a deckling device fitting between said apron and regulating plate and slidably adjustable therebetween for controlling the width of the flow of stock, said deckling device being adjustable in a vertical direction to fit the space between said apron and vertically adjustable regulating plate.
10. In combination in a paper making machine, a head box having a discharge opening, an apron extending outwardly from the lower edge of said opening, means adjacent the outer end of said apron for receiving the paper stock flowing over the apron from said head box, a regulating plate overlying said apron for controlling the depth of the flow of stock over said apron, and a deckling device fitting between said apron and regulating plate, slidably adjustable therebetween, for controlling the width of the flow of stock, said deckling device including a back wall

- portion extending crosswise of the machine, fitting between the apron and regulating plate and engaging a portion of the flow box adjacent one end of the discharge opening, 5 thereby serving to close a portion of said opening, and a side wall portion extending lengthwise of the machine from the inner end of said back wall portion and fitting between said apron and regulating plate, there- 10 by to serve as a guide for one edge of the flow of stock.
11. In combination in a paper making machine, a head box having a discharge opening, an apron extending outwardly from the lower edge of said opening, means adjacent the outer end of said apron for receiving the paper stock flowing over the apron from said head box, a vertically adjustable regulating plate overlying said apron for controlling the 15 depth of the flow of stock over said apron, and a deckling device fitting between said apron and regulating plate, slidably adjustable therebetween, for controlling the width of the flow of stock, said deckling device in- 20 cluding a vertically, resiliently extensible back wall adapted to adjust itself to fit the space between said regulating plate and apron, said extensible back wall engaging a portion of the head box adjacent one end of 25 the discharge opening and serving to close an end portion of said opening, and a vertically, resiliently, extensible side wall extending lengthwise of the machine from the inner end of said back wall, adapted to ad- 30 just itself to fit the space between said regulating plate and apron, and thereby effective to serve as a guide for the adjacent edge of the flow of stock between said regulating plate and apron.
12. In combination in a paper making machine, a head box having a discharge opening, an apron extending outwardly from the lower edge of said opening, means for receiving the paper stock which flows from said head box 40 and over said apron, a regulating plate pivotally mounted on a horizontal axis adjacent the upper edge of said discharge opening, means for swinging said regulating plate on its pivot for adjusting the depth of the flow of stock between said apron and the plate, a deckling device between said apron and regulating plate including a spring actuated, vertically extensible wall portion, automatically effective to maintain itself so extended that it closely fits the space between said regulating plate and apron for guiding one edge of the flow of stock in said space.
13. In a paper making machine, the combination of a head box having a side provided with a discharge opening, a vertically adjustable gate forming a portion of said side adjacent the upper edge of the discharge opening and operable to adjust the vertical depth of said opening, an apron extending 50 outwardly from the lower edge of said dis- charge opening, a regulating plate overlying said apron and pivotally mounted on said adjustable gate so as to be vertically adjustable therewith, means for swinging said regulating plate on its pivot to control the depth of the flow of stock over said apron, a deckling device disposed between said apron and regulating plate and slidably adjustable therebetween, said device including a vertically extensible back wall portion adapted to close an end portion of said discharge opening and a vertically extensible side wall portion for guiding one edge of the flow of stock between said apron and plate, resilient means normally tending to extend said back and side walls so as to cause the same to closely fit the space between said apron and regulating plate, and means for effecting adjustment of said deckling device crosswise of the machine between said apron and regulating plate.
14. In a paper making machine, the combination of a head box having a side provided with a discharge opening, a vertically adjustable gate forming a portion of said side adjacent the upper edge of the discharge opening and operable to adjust the vertical depth of said opening, an apron extending outwardly from the lower edge of said discharge opening, a regulating plate overlying said apron and pivotally mounted on said adjustable gate so as to be vertically adjustable therewith, means for swinging said regulating plate on its pivot to control the depth of the flow of stock over said apron, a deckling device disposed between said apron and regulating plate and slidably adjustable therebetween, said device including a vertically extensible back wall portion adapted to close an end portion of said discharge opening and a vertically extensible side wall portion for guiding one edge of the flow of stock between said apron and plate, resilient means normally tending to extend said back and side walls so as to cause the same to closely fit the space between said apron and regulating plate, and means for effecting adjustment of said deckling device crosswise of the machine between said apron and regulating plate.
15. In a paper making machine, the combination of a head box having a discharge opening, an apron extending outwardly from the lower edge of said discharge opening, means adjacent the outer edge of said apron for receiving a flow of paper stock from said head box, a regulating plate overlying said apron for controlling the depth of the flow of stock over said apron, a deckling device disposed between said apron and regulating plate and slidably adjustable therebetween, crosswise of the machine, for regulating the width of the flow of stock between said apron and regulating plate, a deckle strap for controlling the width of the flow of stock on said means, a pulley for guiding said deckle strap, means for mounting said pulley so as to permit adjustment thereof crosswise of said receiving means for effecting adjustment of the

deckle strap and consequent adjustment of the width of said flow of stock on said receiving means, and means for simultaneously adjusting said deckling device and said deckle strap guide pulley.

16. In a paper making machine, the combination of a head box having a discharge opening, means for receiving a flow of stock from said head box, means intermediate the discharge opening of said head box and said receiving means for conducting the paper stock from said head box to said receiving means, a deckling device disposed adjacent said intermediate means for controlling the width of the flow of stock thereover, a deckling device disposed adjacent said receiving means for controlling the width of the flow of stock thereon, and means for effecting simultaneous adjustment of both of said deckling devices.

17. In combination, in a paper-making machine, a paper stock receiving wire, a deckle strap and a pulley normally overlying said wire for guiding said strap, an arm carrying

said pulley, and means for mounting said arm on a relatively stationary portion of the machine so as to permit said arm and pulley to be moved laterally outwardly from normal position overlying said stock-receiving wire to afford free access to said wire.

18. In a paper-making machine, the combination of a head box having a discharge opening, a wire for receiving a flow of paper stock from said head box, an apron for conducting stock from said discharge opening to said wire, a vertically adjustable regulating plate overlying said apron for controlling the depth of the flow of stock thereover, and a deckling device for controlling the width of said flow between said apron and regulating plate, said device being self adjusting to fit the vertical space between said apron and regulating plate, and means for mounting said deckling device so as to permit adjustment thereof crosswise of said apron between said apron and regulating plate.
